Inventor,
John P. Ball.

Patented Apr. 10, 1923.

UNITED STATES PATENT OFFICE.

JOHN P. BALL, OF CHICAGO, ILLINOIS.

AEROPLANE GUN MOUNTING.

Application filed July 13, 1921. Serial No. 484,389.

To all whom it may concern:

Be it known that I, JOHN P. BALL, a citizen of the United States, and a resident of the city of Chicago, county of Cook, State 5 of Illinois, United States of America, have invented a new and useful improvement in aeroplane gun mountings for coast protection and for the protection of cities and villages from the attack of hostile aer- 10 planes.

This invention relates to devices for mounting a rotating gun within a revolving gun carriage on a set of revoluble ribs and arranged so that while in fighting action the 15 gun may be swung into any direction above or below the aeroplane within the scope of said revoluble ribs, and while at rest the gun may be concealed within the body of said aeroplane.

20 This invention also relates to devices for supporting an operator's chair along with said gun carriage and revolving therewith, a turntable device for controlling the field of action of said gun in a horizontal circle 25 and axial bearings for governing the elevation or depression of the gun in a vertical circle, means for giving motion to the gun in a vertical circle about the main hinged axis of the aeroplane, means for giving motion to the gun in a horizontal circle within the turntable, and means for giving motion to the gun in a vertical circle through the gun-axial-bearings.

30 My invention also includes means for placing the gun in a concealed position in the body of the aeroplane while the mechanism is not in a fighting position.

35 My invention provides improvements especially applicable to fighting devices in 40 aeroplanes of this general character, and in its preferred form it utilizes two main longitudinal frame members supporting the body of the aeroplane, two pivoted bar members supporting a gun carriage and an operator's 45 chair and hinged to the main frame members at approximately the center of gravity of the aeroplane, an open passage in the body of the aeroplane so that the gun carriage and operator's chair may revolve on the piv- 50 oted bars about the axial center pin supporting the hinged joint.

55 In the accompanying drawings which show certain adaptations of my invention Figure 1, is a cross-sectional view showing the gun and gun carriage in a fighting position, suspended by the pivoted bar members

from the center of the aeroplane. Fig. 2 shows a plan of the gun and gun carriage together with the operator's chair suspended in the area passage of the aeroplane. Fig. 60 3 shows a longitudinal section of the gun carriage and turntable together with the mechanism for revolving the hinged ribs and directing the range of the gun.

65 Referring to the drawings A indicates the main longitudinal frame members, B the pivoted bar members, C the central hinge, D the turntable, E the gun carriage, F the operator's chair, G a gun, H the mechanism for revolving the pivoted bar members, I the mechanism for revolving the carriage in the turn table, J the mechanism for elevating and declining the gun, K the operator's chair supports. L represents an opening in the center approximately of the aeroplane to 70 allow the gun carriage and parts to revolve about the central axis.

75 Referring to Figs. 1 to 3, I will now describe in detail the preferred form of my invention in the adaptation herein illustrated.

80 There are two main longitudinal frame members, the basic support of the aeroplane; these main longitudinal frame members are situated longitudinally with the body of the machine and are applicable to any size or shaped aeroplane and are constructed of any suitable material and of suitable size to support the designed parts. There are two piv- 85 oted bar members B for the gun carriage 90 support and they also consist of suitable material and designed of sufficient size to carry the suspended members in any position and at any angle; these pivoted bars are supported to the main longitudinal frame 95 members by means of hinges as at C which consist of bolts as shown at 1 and I bars as at 2 in Fig. 3. The I bars that form the pivoted bars are free to rotate on the pins or bolts at 1 which are held laterally in 100 place by means of the nut heads 3 as in Fig. 2.

105 The turntable D consists of a ring of sufficient thickness to contain an inner slot 5 to accommodate the gun carriage wheel 6. The turn table is bolted to the hinged rings as at 4 in Fig. 3.

110 The gun carriage E consists of supporting rods 7 bolted to the wheel 6 as shown at 8 and is free to revolve horizontally in the turn table ring 5. The gun carriage supports the gun by an axle as at 9 so that the

gun is free to move vertically in the axial bearings.

As thus far described the gun is given three revolving motions; 1st the primary motion, the gun, the gun carriage and parts together with the hinged ribs revolve vertically about the main axis of the aeroplane; 2nd the secondary motion, the gun, gun carriage and parts revolve horizontally in the turntable fixed in the hinged ribs; 3rd, the tertiary motion, the gun moves in a vertical circle through the axial gun bearings.

The gun operator's chair F is supported from the gun carriage by means of the rods K which are bolted at one end to the gun carriage as at 9^a in Figure 3 and carrying the operator's chair at the other end with a free joint as at 10; so that the operator's chair may rotate horizontally with the gun carriage E and vertically with the axial bearings 10.

The principal purpose of my invention is to suspend a gun from an aeroplane in such a manner that a range in any direction of a sphere may be attained; the center of the sphere being the center of the armored aeroplane. In order to give motion to the gun in any direction any usable power may be employed such as compressed air applied to a mechanism of cog wheels. The primary motion is shown as a combination of cog wheels as at 12 and an air power 13. The secondary motion is shown as a combination of cog wheels as at 14 and air power 15. The tertiary motion is shown as a combination of cog wheels at 16 and air power at 17 in Fig. 3.

It is evident that by these three motions the gun may be concealed within the body of the aeroplane, which is also a feature of my invention as a disappearing gun.

The transmission of power from the aero-motor to the mechanism controlling the position of the gun is also a feature of my invention and is shown by an air compressor 19 and a compressed air tank at 20. The compressed air power may be controlled by the aero operator, instructions being given by the gun operator by means of the telephone wire as shown at 21.

As thus far described it will be seen that two principal positions of the gun are attained, the one concealed and the other in fighting action, these being described herein in the preferred form of my invention.

What I claim is:

1. In an air-craft the combination of a set

of main longitudinal frame members spaced apart, a supplementary set of pivoted bars hinged at their rear ends to the central point on said main frame members so as to swing downwardly, a gun and a gun operator's chair secured on the outer ends of said supplementary bars, gears and geared wheels located on said supplementary bars and said main transverse frame members and adapted to engage gears to maintain the supplementary bars and gun and gun operator's chair in normal position, means for controlling the movement of said supplementary bars with the gun and the gun operator's chair from a normal into a vertical position beneath said main transverse frame members, means whereby the speed of the downward movement of said supplementary bars may be controlled and means whereby said supplementary bars may be again raised to an upward and normal position.

2. In a flying machine the combination of longitudinal frame members disposed at longitudinal axis of the machine and extending from front to rear thereof, supplementary bars pivoted at the rear ends to said longitudinal frame members substantially at the longitudinal center so as to revolve in a vertical circle, a turn table secured in a transverse position to the free ends of the supplementary bars and independent of the machine body, a gun operator's chair revolvably mounted in said turntable and adapted to swing in trunnions and balance so as to maintain an upright position at all times, means for revolving vertically said supplementary bars and means for revolving said gun operator's chair.

3. In a flying machine, main longitudinal frame members disposed lengthwise of the body of the machine in the same plane, supplementary pivoted bars spaced apart and hinged at one end to said main longitudinal frame members and adapted to swing in a vertical circle, an auxiliary operator's chair independent of the main operator's chair, and pivotally secured to the other end adapted to rotate in a circle, means for revolving said supplementary bars, means for rotating said auxiliary operator's chair and means of communication between said auxiliary operation and the main machine operator.

JOHN P. BALL.
